UNITED STATES PATENT OFFICE.

SALLY MAYER AND HERMANN NAHRSTEDT, OF ST. LOUIS, MISSOURI.

HUMIDIFIER FOR OVENS.

Application filed March 15, 1926. Serial No. 94,707.

This invention relates to improvements in humidifiers for ovens.

An object of the invention is to provide a humidifier particularly adapted to be used 5 in connection with bake ovens to generate and inject into the oven a quantity of steam for the purpose of humidifying the atmosphere within the oven.

Additional advantages of the construction 10 will appear from the following detailed description thereof, taken in connection with the accompanying drawing, in which,

Fig. 1 is a fragmentary section of the 15 hearth of the oven with the humidifier shown in association therewith.

Fig. 2 is a front elevation of the oven 20 wall showing an end elevation of the humidifying device with its connections.

Fig. 3 is a vertical section through the 25 oven wall taken on the line 3—3 of Fig. 1.

Fig. 4 is a sectional view through the 30 humidifying device.

Fig. 5 is a vertical section on the line 35 5—5 of Fig. 4.

In the embodiment of the invention illustrated in the drawing, the device is shown 40 as incorporated in an oven construction, the front wall 1 of which is shown in Fig. 2 of the drawing. In such oven construction, the 45 over chamber 2 is disposed above the fire arch of the furnace and is separated therefrom by masonry construction filled in with sand or other material, through which the heat from the furnace is transmitted to the 50 oven chamber.

The upper portion of the intermediate 55 wall within the oven chamber is faced with tiles to form the hearth or bottom wall 3 of the oven. In the intermediate masonry wall 4 that separates the furnace from the oven 60 chamber, there is provided a longitudinal cavity forming a chamber 5. This chamber is constructed in the masonry of the separating wall 4, preferably intermediate the oven 65 door openings 6 of the oven and at a point below the bottom wall or hearth of the oven.

Within the cavity thus provided is placed 70 the humidifying device that includes a rectangular box-shaped lower section 7 formed 75 from a bottom wall 8, side walls 9 and end walls 10. The end walls have an integral 80 extension 11, the edges of which deflect inwardly and to which are connected downwardly inclined side walls 12 and a top wall 85 13. The construction is such that there is 90 a longitudinal open space 14 at each side of 95

the device between the top edge of the walls 9 and the lower edge of the walls 12.

The dome or extension of the humidifier 100 formed from the outwardly flaring side 60 walls 12 and the top wall 13 provides a chamber in which the water or other liquid introduced into the device is vaporized, the vapor passing outwardly through the longitudinal openings 14 and into that portion of 65 the chamber 5 unoccupied by the humidifying device, from which chamber the steam passes upwardly between the tiles of the 70 hearth that extend over and form the top wall of the chamber 5, and into the oven 75 chamber.

It will be noted by reference to Figs. 3 and 5 that the bottom wall 8 inclines downwardly toward the front of the device and that on the inner surface of the bottom wall 75 8 are a series of ribs 15, the purpose of which is to form riffle plates over which unvaporized liquid in the bottom of the trough portion of the humidifier is required to flow, keeping the bottom surface partially submerged. 80

The liquid used for forming the vapor is admitted to the humidifying chamber through a spray pipe 16, longitudinally disposed within the humidifier and supported 85 by the end walls 10—11. The pipe 16 is closed at its rearward end and has a projection 17 that extends into an opening in the rear wall of the humidifier and the forward end of the pipe 16 extends outwardly 90 through an opening in the front wall thereof and is connected with a supply pipe 18. Through the upper portion of the pipe 16, 95 there is a spaced series of jet openings 19 through which the liquid from the pipe 16 is sprayed against the dome portion of the 100 humidifier.

Inasmuch as the device is supported in the oven construction in the wall between the furnace arch and the oven, it will be sufficiently heated throughout its surface to vaporize a substantial portion of the liquid admitted through the pipe 16, which vapor or steam escapes into the chamber 5 and thence through the parting between the tiles 105 of the hearth over the chamber 5 into the oven.

The amount of liquid admitted to the 110 humidifier is controlled by a self-closing valve 20 so that at predetermined intervals by the operation of the valve, a quantity of water may be admitted to the humidifier, and

thereby the proper humidity of the atmosphere within the oven may be maintained. The excess liquid accumulates in the trough-like portion in the bottom of the humidifier, 5 and is continuously vaporized by the heat radiated from the walls of the chamber. In order to prevent an excess accumulation of liquid in the bottom of the trough, a discharge pipe 21 is connected into the forward 10 end of the humidifier near the bottom wall thereof.

It will be understood from the foregoing description that the humidifier may be cheaply constructed and may be installed in 15 any standard oven construction, and that it will be effective in maintaining the proper humidity required for the proper operation of the oven. If desired, the supply liquid may be preheated in order to prevent undue 20 cooling of the walls of the humidifier and facilitating the conversion of the liquid into the humidifying vapor.

We are aware that the invention may be modified in various particulars without departing from the spirit and scope thereof, 25 and we do not limit ourselves unessentially.

What we claim and desire to secure by Letters Patent is:—

1. In a bake oven, the combination with a 30 fire chamber and an oven with an intermediate horizontally disposed wall therebetween, of a chamber formed in said wall, a humidifying device mounted in said chamber comprising a trough portion and a dome portion with intermediate outlet passages, a 35 spray pipe connected into said humidifying device, and means for controlling the supply of liquid to said spray pipe.

2. In an oven, the combination with an 40 oven chamber, a recess formed in the bottom wall of the chamber, said recess being walled at the top by spaced tile of the hearth of the oven, a humidifying device spaced from the

side walls of said recess, said humidifying device including a housing with outlet openings therein, a spray pipe longitudinally disposed within said housing, and means for admitting measured quantities of liquid to said housing. 45

3. In an oven, the combination with an oven chamber, a recess formed in the bottom wall of the chamber, said recess being walled at the top by spaced tile of the hearth of the oven, a humidifying device spaced from the side walls of said recess, said humidifying device including a housing with outlet openings therein, a spray pipe longitudinally disposed within said housing, means for admitting measured quantities of liquid to said housing, and a drain pipe for 60 draining the excess liquid from said housing. 55

4. A humidifying device comprising a housing having a trough-shaped lower portion and a dome with inclined side walls, 65 with a space between said dome and said lower portion, a pipe running longitudinally through said housing having a plurality of outlet openings therein for ejecting fluid against the walls of said dome portion, and 70 means for controlling the admission of liquid to said pipe. 75

5. A humidifying device comprising a housing having a trough-shaped lower portion and a dome with inclined side walls, 80 with a space between said dome and said lower portion, a plurality of transversely extending ribs on the bottom wall of said trough portion, a pipe running longitudinally through said housing having a plurality of outlet openings therein for ejecting fluid against the walls of said dome portion, and means for controlling the admission of liquid to said pipe. 85
